US0D1030323S

(12) **United States Design Patent** (10) **Patent No.:** **US D1,030,323 S**
(45) **Date of Patent:** **** Jun. 11, 2024**

(54) **UNDER-SINK ORGANIZER**

(71) Applicant: **SHENZHEN NADAHAI TRADING CO., LTD.**, Shenzhen (CN)

(72) Inventor: **Yonggang Guo**, Shenzhen (CN)

(73) Assignee: **SHENZHEN NADAHAI TRADING CO., LTD.**, Shenzhen (CN)

(**) Term: **15 Years**

(21) Appl. No.: **29/865,332**

(22) Filed: **Jul. 20, 2022**

(30) **Foreign Application Priority Data**

Jul. 7, 2022 (EM) 009077407

(51) **LOC (14) Cl.** **06-04**

(52) **U.S. Cl.**

USPC **D6/675.1**; D3/313

(58) **Field of Classification Search**

USPC D3/311, 295, 304, 310, 313; D34/21;

D6/675, 675.1, 705, 562

CPC B65D 21/0234; B42F 7/12; A47B 77/06;

Assistant Examiner — Alexandria Dubus

(57) **CLAIM**

The ornamental design for an under-sink organizer, as shown and described.

DESCRIPTION

FIG. 1 is a bottom perspective view of an under-sink organizer showing my new design;

FIG. 2 is a top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 1. The dash-dash broken lines in the drawings depict portions of the under-sink organizer that form no part of the claimed design. The dot-dash broken lines represent the boundary of the enlarged portion and form no part of the claimed design.

1 Claim, 9 Drawing Sheets
